UNITED STATES PATENT OFFICE.

WILLIAM I. FIELDING, OF NEW BRITAIN, CONNECTICUT.

BOLSTER BED-BOTTOM.

SPECIFICATION forming part of Letters Patent No. 323,572, dated August 4, 1885.

Application filed January 21, 1885. (No model.)

To all whom it may concern:

Be it known that I, WILLIAM I. FIELDING, a citizen of the United States, residing at New Britain, in the county of Hartford and State 5 of Connecticut, have invented certain new and useful Improvements in Bolster Bed-Bottoms, of which the following is a specification.

In the accompanying sheet of drawings, Figure 1 is a plan view of my bed-bottom, and 10 Fig. 2 is a side elevation of the same.

I have illustrated this bed-bottom as attached directly to a frame which also constitutes a bedstead.

A designates the side rails, and B the end rails. The main fabric C is attached to the frame by means of a series of longitudinally-acting springs, *a*, at each end. I prefer to make this fabric in a series of metallic links. The parts thus far described are the same as 15 have been previously manufactured and sold in the market. At the head of the bed I attach a bolster-frame consisting of an end bar, D, and two side bars, *b*, which are pivoted to the side rails A, as shown. Hinged braces 20 *c*, having an inwardly-projecting lug, *d*, are pivoted to the side bars of the bolster-frame, and the side rails of the main frame are each provided with a rack, *f*, the teeth of which 25 engage the lugs *d*, so as to hold the bolster-frame at any desired elevation. A supplementary flexible fabric, E, is secured by one 30 edge to the main fabric C at a point near the middle of the length of said main fabric, while its opposite edge is connected with the end 35 bar, D, of the bolster-frame by means of a series of longitudinally-acting springs, *a'*. It should be noticed that there is no cross-bar or anything else to interfere with the flexible character of the bed-bottom at any point be- 40 tween the series of springs at the foot and either series of springs at the head. When the bolster-frame is dropped into the position indicated by broken lines in Fig. 2, the sup- 45 plementary fabric will lie close to the main fabric, and the bed-bottom will act the same as if there were no bolster thereon, the sup- 50 plemental flexible fabric not interfering in the least with the flexibility and consequent ease and comfort of the main fabric. When the 55 bolster-frame is elevated and there is no one

occupying the bed, the supplementary fabric will be slack, but so soon as a weight is thrown upon the main fabric to depress it, as that of an occupant, the depression of the main fabric in the middle will draw the supplementary 55 fabric taut and properly support the part of the occupant which lies upon the bolster.

By means of the bolster-frame having the supplementary fabric and springs, a bolster is furnished which has all the elasticity of the 60 main fabric and which does not in any manner interfere with the operation of the main fabric.

I have previously made and sold a bed like the main bed, which was provided with a similar bolster-frame having a series of transverse rods for a supporting-surface; but such a bolster, it will readily be seen, does not furnish that ease and comfort to the occupant which my new bolster does, and, furthermore, when 70 let down it destroyed in a measure the ease and comfort of the main fabric.

I prefer in all cases to employ a series of springs at both the head and foot of the main fabric, and also at the head of the bolster-frame; but in case a bed should be made with 75 series of springs at the foot only of the main fabric, then the springs may also be omitted from the bolster.

If desired, instead of a fabric made elastic 80 longitudinally by springs, the ordinary woven-wire bed or other bed-bottoms having a suspended flexible fabric, may be employed for the bed proper.

I am aware that prior patents show, first, a 85 bed-bottom consisting of a series of longitudinal sheet-metal strips connected to the end rails of the bed-frame and supported at the middle portion by two rigid cross-bars which rest upon springs; said bed-bottom was also 90 provided with a bolster-frame having metal strips attached thereto by one end while the opposite end of said strips was attached to the middle cross-bars of the bed-bottom; and, second, a bed-bottom consisting of a series of 95 longitudinal springs attached to the end rails of the bed-frame and supported at the middle portion of the bed-bottom by vertical coiled springs that rest upon cross-bars. Said bed-bottom was also provided with a bolster-frame 100

having longitudinal springs attached to its cross-bars, one of which cross-bars extended transversely across the bed-bottom near the middle of its length. All of said prior art is 5 hereby disclaimed.

I claim as my invention—

The combination of the main bed-bottom, consisting, essentially, of a flexible fabric extending substantially the whole length of the 10 bed, and suspended upon a frame with the flexibility of its middle portion unimpaired,

the bolster-frame, and the supplementary fabric with one of its edges connected to the cross-bar of said bolster-frame and its opposite edge connected to the middle portion of the flexible fabric which forms the main bed-bottom, substantially as described, and for the 15 purpose specified.

WILLIAM I. FIELDING.
